US00D939261S

(12) **United States Design Patent** (10) Patent No.: **US D939,261 S**
Baur (45) Date of Patent: **** Dec. 28, 2021**

(54) **COFFEE MAKER**

(71) Applicant: **Jura Elektroapparate AG**,
 Niederbuchsiten (CH)

(72) Inventor: **Philipp Baur**, Utzenstorf (CH)

(73) Assignee: **Jura Elektroapparate AG**,
 Niederbuchsiten (CH)

(**) Term: **15 Years**

(21) Appl. No.: **35/509,447**

(22) Filed: **Apr. 30, 2020**

(80) **Hague Agreement Data**

Int. Filing Date: **Apr. 30, 2020**
 Int. Reg. No.: **DM/208137**
 Int. Reg. Date: **Apr. 30, 2020**
 Int. Reg. Pub. Date: **May 22, 2020**

(51) LOC (13) Cl. **07-02**
 (52) U.S. Cl. **USPC** **D7/309**

(58) **Field of Classification Search**
 USPC D7/300, 301, 306, 309, 311, 312, 313,
 D7/332, 337, 339, 347, 348, 362, 367,
 D7/368, 376, 377, 378, 381, 383, 399,
 D7/665
 CPC .. A47J 31/44; A47J 31/52; A47J 43/04; A47J
 43/044
